DESIGN FOR A HOLDER FOR GARBAGE CANS

Frank Crossley, Philadelphia, Pa.

Application May 4, 1943, Serial No. 110,110

Term of patent 14 years

To all whom it may concern:

Be it known that I, Frank Crossley, a citizen of the United States, residing at Philadelphia, in the county of Philadelphia and State of Pennsylvania, have invented a new, original, and ornamental Design for a Holder for Garbage Cans, of which the following is a specification, reference being had to the accompanying drawing, forming part thereof.

I claim:

The ornamental design for a holder for garbage cans, as shown.

FRANK CROSSLEY.
